(57) **CLAIM**

The ornamental design for a beverage container, as shown and described.

DESCRIPTION

FIG. 1 is a top perspective view of an ornamental design for a beverage container, showing our new design.

FIG. 2 is a bottom perspective view of the beverage container of FIG. 1.

FIG. 3 is a front elevation view of the beverage container of FIG. 1.

FIG. 4 is a top plan view of the beverage container of FIG. 1.

FIG. 5 is a bottom plan view of the beverage container of FIG. 1.

FIG. 6 is a sectional view of the beverage container of FIG. 1 upon the plane 6 indicated in FIG. 4; and,

FIG. 7 is a sectional view of the beverage container of FIG. 1 upon the plane 7 indicated in FIG. 4.

The left-side elevation view, right-side elevation view, and back elevation view are identical to the front elevation view.
